UNITED STATES PATENT OFFICE.

WILLIAM A. GILE, OF STONEHAM, MASSACHUSETTS, ASSIGNOR TO GILE ENGINE COMPANY, OF BOSTON, MASSACHUSETTS, A CORPORATION OF MASSACHUSETTS.

INTERNAL-COMBUSTION ENGINE.

Application filed August 26, 1922. Serial No. 584,455.

To all whom it may concern:

Be it known that I, WILLIAM A. GILE, a citizen of the United States, and a resident of Stoneham, in the county of Middlesex 5 and State of Massachusetts, have invented a new and useful Improvement in Internal-Combustion Engines, of which the following is a specification.

My invention relates to internal combustion engines and more especially to single-acting engines of the combined pump and motor-cylinder type, and its object is to provide a simple and efficient means actuated directly by the main crank for controlling 10 the motion of the sub-piston positively throughout the entire cycle with a minimum of friction.

In my application Serial No. 96,421 filed May 16, 1916, I described means actuated 20 directly by the main crank for controlling the motion of the sub-piston positively throughout the entire cycle in such manner that the sub-piston travelled in contact with the power piston until the sub-piston 25 reached substantially the end of its power stroke or at least for a substantial portion of the power stroke of the power piston, and subsequently moved in the opposite direction thereby drawing in a fresh charge of 30 fuel and ejecting the burnt gases of the previous explosion.

By means of the present invention which is an improvement on that disclosed in my application aforesaid, the same movements 35 of piston and sub-piston are created by mechanism which may be constructed more economically and operated with less friction for the reason that the angles between the various links, rods and arms of the mechanism actuated directly by the main crank for controlling the motion of the sub-piston are less acute than in the case of the engine described in my earlier application.

With the foregoing objects in view, my invention 45 comprises a mechanism actuated directly by the crank for causing the power piston and the sub-piston to travel in contact until the sub-piston reaches substantially the end of its power stroke, or at least 50 throughout a substantial portion of such power stroke, such mechanism involving a link pivotally connected at one end to the sub-piston rod and means for guiding the

other end of said link preferably rectilinearly together with other means for limiting the rectilinear or other movement thereof as distinguished from the mechanism of my prior application in which the end of the corresponding link is pivotally connected to the engine frame. My invention involves 55 also a slideable spring-pressed pivotal connection between the sub-piston rod and the link above mentioned, whereby any lost motion due to wear in the bearings may be taken up so that the sub-piston will be held firmly 60 against the power piston during the power stroke, together with various other improvements hereinafter more fully set forth.

An illustrative embodiment of my invention is shown in the accompanying drawings in which:

Fig. 1 is an elevation of an internal combustion engine embodying my improvements, certain parts being shown in central vertical section;

Fig. 2 is an elevation as viewed from a point ninety degrees from the plane of Figure 1;

Figures 3 to 12 inclusive are diagrams showing the positions of the moving parts 80 at various points in the cycle.

In the particular drawings selected for more fully disclosing my invention, 20 represents the crank case in which the main crank 21 is journalled. Bolted to said case is a cylinder 22 in which the power piston 23 and sub-piston 24 are arranged to reciprocate. The combustion chamber end of the cylinder is counterbored as shown at 25 in the manner described in detail in U. S. Letters Patent, No. 1,335,329 issued March 30, 1920 on the application of F. H. Gile, for the purpose of obtaining perfect mixing of the gaseous fuel and complete combustion thereof.

The power piston is pivotally connected by the double pitman 26, 26 to the crank pin 27 of the crank 28, which is provided with a counterbalance 29 secured thereto by the screws 30. It will be noted that the main crank 21 is offset a short distance to the left of the longitudinal axis of the cylinder.

The sub-piston 24 which is relatively light, imperforate and valveless is arranged between the power piston and the combustion 105 chamber A, and is provided with a rod 31

passing through a longitudinal bore in the central core 31' of the power piston. The lower end of the sub-piston rod is pivoted to the link 32 by means of a slideable spring-pressed pivotal connection, said connection consisting in the present instance of a pin 33 inserted in a bearing provided with the bushing 34 in the head 35 of said link 32, through a bore in which pin the reduced end 5 portion 36 of said rod 31 passes, a collar 37 being interposed between said pin and a shoulder on said rod, and the collar 38 provided with the flange 39 between the lower portion of said pin and the spiral spring 40, the tension of which spring may be adjusted 10 by means of the nut 41 threaded to the lower end of the reduced portion 36 of said sub-piston rod.

The other end of the link 32 is pivotally connected at 42 to a plug 43 which in the present instance is slotted to receive said end of said link, and a cap 44 is bolted or otherwise secured to the engine frame for receiving said plug and guiding the same rectilinearly, the head of said plug preferably being perforated as shown at 45 in order to prevent compression of air in the space between its outer face and the inner face of the cap. At the point 46 intermediate the 20 ends of said link 32, a shorter link 47 is pivoted thereto, and the other end thereof is pivoted to the engine frame at 48, the said link 47 serving as a means for limiting the reciprocating movement of the plug 43, although 25 obviously other means may be employed for this purpose. The upper and lower portions of the head 35 of the link 32 are slotted as shown at 49, 49 to permit of free arcuate movement of said link with respect to the sub-piston rod 31.

The ends of the rod 50, the upper end terminating in the fork 50', are pivotally connected to the link 32 and the rocker arm 51 at the points 52, 53 respectively, said 30 rocker arm being pivoted to the engine frame at the point 54. In the present instance the rocker arm 51 consists of two parallel arms clamped together by the bolt 55 against the hub 56 of the cross-shaft 57, which has its bearings in the studs 58, 58 arranged in the bosses 59, 59, although obviously I do not limit myself to this construction. The upper ends of the arms 51 are bored to receive the pin 60, the ends of 40 which extend laterally from said arms and the enlarged central portion 61 of which having its center at the point 53 affords a bearing for the hub of the rod 50. A bolt 62 passes through the arms 51 and the enlarged central portion 61 of said pin 60 to prevent the latter from turning with respect to said arms. The lower ends of the arms 63 are pivotally connected to the pins 60, the center of which is shown at 64, the angle between the points 53, 54 and 64 being

in the present instance approximately five degrees, and the upper ends of said arms 63 are connected by the hubs 65, 65 to the wrist pin 27 of the crank shaft, between the crank arms 28 and the box 66 of the double 70 pitman 26, the center of such connection being indicated at 67, while the center of the connection of the pitman to the wrist pin is shown at 68, the angle between the points 67, 69 which is the center of the main shaft 75 21 and 68 being approximately five degrees, so that, as the direction of rotation is clockwise, the crank shaft has a lead of five degrees over the arms 63. The upper end of the pitman 26 is articulated to the stud 70 80 arranged in bosses on the interior walls of the power piston.

The cylinder is provided with an intake port 71, and an exhaust port 72, the latter being controlled by the exhaust valve 73 85 actuated at the proper times by mechanism which is well understood and constitutes no part of my invention.

An explosion of the compressed charge in the combustion chamber A acts directly on the head of the sub-piston and by the latter is communicated to the power piston. It is absolutely necessary that the two pistons shall travel at the same rate of speed without the slightest relative movement until the 90 sub-piston shall have covered the inner end of the counterbore 25 for the reason that a portion of the effect of the explosion would be exerted against the lower face of said sub-piston in opposition to the force exerted on the upper face thereof if the power piston began to move away from the sub-piston before the latter had covered the inner end of said counterbore. It is essential also that the two pistons should travel in contact at 95 the same rate of speed until substantially the end of the power stroke, or until shortly after the opening of the exhaust valve. Furthermore, it is essential that the subsequent relative movement between the two pistons 100 be created positively, and in fact that the sub-piston should be controlled positively throughout the entire cycle. The positive control of the sub-piston and the positive relative movement thereof with respect to 105 the power piston is created by the main crank 28, which communicates the necessary motion to the sub-piston through the arms 63 and the rocker arm 51, the rod 50 and the link 32. The operation of these elements 110 will be explained by reference to Figures 3 to 12 inclusive on which the several moving parts are indicated by lines identified by reference numerals corresponding to those used on Figures 1 and 2 and provided with 115 exponents to designate the successive positions of said parts.

When both pistons are at the upper ends of their strokes (explosion position) as shown in Figures 1 and 3 and the charge 120

compressed in the combustion chamber, the valve 73 being closed, the charge is fired and the resulting explosion causes both pistons to descend at the same initial rate of speed without any relative movement until the crank, which rotates in the direction of the arrow, has passed from its initial position 28 (Figure 3) through the intermediate positions 28^a, (25 degrees) and 28^b, (50 degrees) to a few degrees past 28^c, (90 degrees). The oscillation of the rocker arms 51 in a clockwise direction draws the link 32 downwardly through the intermediary of the rod 50 and causes the end thereof, pivoted at 42 to the plug 43 to move rectilinearly to the right until the link 47 is in line with the link 32, a few degrees beyond the position indicated in Figure 5, whereupon further rotation of the crank causes said plug to move toward the left until the centers 64, 67 and 69, are in line a few degrees beyond the position indicated in Figure 7, and the rocker arm 51 has its lowermost position, whereupon said plug again travels to the right until the links 37 and 32 are again in line a few degrees beyond the position shown in Figure 9, when further rotation of the crank causes said plug again to move to the left until it again assumes its initial position. Shortly after the crank has passed the position 28^c, the sub-piston has reached the end of its down-stroke just below 24^d and the exhaust valve 73 opens practically simultaneously with or preferably shortly before this point has been reached, so that when the power piston begins to draw away from the sub-piston as indicated in Figure 7, there will be but little pressure exerted on the upper face of said sub-piston. When the sub-piston reaches the end of its down-stroke, its lower face and the upper face of the power piston are practically in line with the fuel inlet. The power piston continues its descent, the crank passing through the positions 28^d, (115 degrees) and 28^e (145 degrees) to 28^f (180 degrees), until it reaches the end of its down-stroke (Figure 9), but immediately after the crank arrived at its position 28^f and while the power piston was descending from 23^a to 23^f the sub-piston began to ascend, the rocker arms being rotated counterclockwise by the movement of the crank beyond its 115 degree position shown in Figure 7, thereby forcing the rod 50 upwardly, so that in the position of the parts represented in Figure 9, the power piston is momentarily stationary and the sub-piston is moving upwardly. The relative movement of the two pistons between the 115 and 180 degree positions of the crank creates a vacuum or a partial vacuum in the space between the same and a charge of fuel is drawn into said space. Simultaneously with the drawing in of such charge, the up-stroke of the sub-piston mechanically expels

the burnt gases of the preceding explosion through the exhaust passage 72, the exhaust valve 73 having been opened shortly before the commencement of the up-stroke of the sub-piston, as above pointed out.

70

The crank continues its clockwise rotation to the position indicated in Figure 10 (225 degrees) and the continued counter clockwise movement of the rocker arm 51 acting on the link 32 through the intermediary of

75

the rod 50 causes the sub-piston to assume the position 24^g just below its explosion position whereby the induction of the fresh charge and the mechanical expulsion of the spent gases are completed. When the crank arrives at position 28^g (270 degrees), the

80

sub-piston has reached its explosion position, the counterbore is uncovered and the power piston having covered the intake port shortly before the crank arrived at its 270 degree position, the continued upward movement of

85

said power piston compresses the charge in the space between its upper face and the lower face of the sub-piston, said charge passing through the annular space between the counterbored head of the cylinder and the sub-piston in a thin cylindrical sheet, thereby effecting the complete mixing of the

90

same as more fully set forth in Letters Patent No. 1,335,329 above mentioned. While the crank is passing from its position 28^g to its initial position through the intermediate position 28^h (315 degrees), the sub-piston remains practically stationary, that

95

is to say, as soon as the points 52, 53, 54 are in line, the sub-piston will have reached a point very slightly higher than its explosion position, as soon as the continued rotation of the crank causes a slight counterclockwise

100

rotation of the rocker arm, the sub-piston settles back a small fraction of an inch, the rod 50 moving slightly downwardly, and as soon as the points 64, 69, and 67 are in line, a few degrees after the crank position 28^h, the resulting clockwise oscillation of the

105

rocker arm will produce a slight upward, and finally a slight downward, movement of the sub-piston which ends when explosion position is reached and the crank is at upper dead center, the two pistons being in

110

contact at that point as shown in Figure 3.

115

It will be noted that by virtue of the location of the center of oscillation 54 of the arm 51 and the general arrangement of the other elements, as distinguished from the construction shown in my application above referred to, the angles between the rod 50 and the rocker arm, as well as between the arm 63 and said rocker arm, are always

120

more obtuse than in the case of the angles between the corresponding members shown in said application, which results in more economical operation on account of the greatly reduced friction between the several

125

parts of the sub-piston control mechanism,

130

and also in less movement of the sub-piston during the rotation of the crank from its position 28° to its initial position.

When the up-stroke of the power piston is completed, ignition occurs and the cycle is repeated, there being one explosion at the end of every up-stroke or one per revolution of the crank shaft.

While I have described in detail the relative movement of the parts which I have found to be satisfactory in practice, it will be understood that I do not limit myself specifically thereto, for said parts may be variously adjusted and timed and other cycles may be effected.

Having thus particularly described an illustrative embodiment of my invention without however limiting the same thereto, what I claim and desire to secure by Letters Patent is:—

1. An internal combustion engine comprising a cylinder, a power piston and an imperforate sub-piston both arranged to reciprocate within said cylinder, said sub-piston being located between the combustion chamber and said power piston, a rod for said sub-piston, a main shaft provided with a crank, means for controlling said sub-piston positively throughout the entire cycle, said means comprising a link, a slidable, spring-pressed, pivotal connection between said rod and said link, a member connecting said means directly to said crank, and means pivotally connecting said power piston to said crank.

2. An internal combustion engine comprising a cylinder, a power piston and an imperforate sub-piston both arranged to reciprocate within said cylinder, a rod for said sub-piston, a main shaft having a crank, and means actuated directly by said crank for causing said pistons to travel at the same rate of speed until the sub-piston reaches substantially the end of its power stroke and for causing, subsequently, positive relative movement between the same, said means comprising a link and a slidable, spring-pressed, pivotal connection between said rod and said link.

3. An internal combustion engine comprising a cylinder, a power piston and an imperforate sub-piston both arranged to reciprocate within said cylinder, said sub-piston being located between the combustion chamber and said power piston, a rod for said sub-piston, a main shaft provided with a crank, means for controlling said sub-piston positively throughout the entire cycle, said means comprising a link, a pivotal connection between said rod and one end of said link, means for guiding the other end of said link rectilinearly, a member connecting said means directly to said crank, and means pivotally connecting said power piston to said crank.

4. An internal combustion engine comprising a cylinder, a power piston and an imperforate sub-piston both arranged to reciprocate within said cylinder, said sub-piston being located between the combustion chamber and said power piston, a rod for said sub-piston, a main shaft provided with a crank, means for controlling said sub-piston positively throughout the entire cycle, said means comprising a link, a pivotal connection between said rod and one end of said link, means for guiding the other end of said link rectilinearly, means for limiting the rectilinear movement of said end of said link, a rocker arm, a rod pivotally connecting said link and said rocker arm, a member pivotally connecting said rocker arm directly to said crank, and means pivotally connecting said power piston to said crank.

5. An internal combustion engine comprising a cylinder provided with a combustion chamber at one end only, an imperforate sub-piston and a power piston both arranged to reciprocate within said cylinder, said sub-piston having a single head located between said combustion chamber and said power piston, a rod for said sub-piston, a main shaft having a crank, means for causing the sub-piston to travel in contact with the power piston during a substantial portion of the power stroke and for causing, subsequently, positive relative movement between said pistons, said means comprising a link pivotally connected at one end to said rod, a cap, a plug arranged to reciprocate in said cap, means pivotally connecting the other end of said link to said plug, means limiting the reciprocating movement of said plug, a rod pivotally connected to said link, a rocker arm pivotally connected to said rod, an arm pivotally connecting said rocker arm to said crank, and means pivotally connecting said crank to said power piston.

6. An internal combustion engine comprising a cylinder provided with a combustion chamber at one end only, an imperforate sub-piston and a power piston both arranged to reciprocate within said cylinder, said sub-piston having a single head located between said combustion chamber and said power piston, a rod for said sub-piston, a main shaft having a crank, means for causing the sub-piston to travel in contact with the power piston during a substantial portion of the power stroke and for causing, subsequently, positive relative movement between said pistons, said means comprising a link, a pivotal connection between said rod and one end of said link, means guiding the other end of said link rectilinearly, means limiting the rectilinear movement of said end of said link, a rocker arm having one end pivoted to the engine frame, a rod pivotally connected at one end to said link, an arm pivotally and eccentrically connected at one end to

said crank shaft, and means pivotally connecting the other ends of said rod and arm at different points to the other end of said rocker arm.

- 5 7. An internal combustion engine comprising a cylinder provided with a combustion chamber at one end only, an imperforate sub-piston and a power piston both arranged to reciprocate within said cylinder, 10 said sub-piston having a single head located between said combustion chamber and said power piston, a rod for said sub-piston, a main shaft having a crank, said main shaft being offset from the longitudinal axis of 15 said cylinder, means for causing the sub-piston to travel in contact with the power piston during a substantial portion of the power stroke and for causing, subsequently, positive relative movement between said pistons, and a member connecting said means 20 directly to said crank.

8. An internal combustion engine comprising a cylinder, a power piston and an imperforate sub-piston both arranged to reciprocate within said cylinder, a rod for said sub-piston, a main shaft having a crank, and means actuated directly by said crank for causing said sub-piston to travel in contact with said power piston during a substantial 30 portion of the power stroke and for causing subsequently positive relative movement between said pistons, said means comprising a link and a slid able, spring-pressed, pivotal connection between said rod and said link.

35 9. An internal combustion engine comprising a cylinder, a power piston and an imperforate sub-piston both arranged to reciprocate within said cylinder, said sub-pis-

ton being located between the combustion chamber and said power piston, a rod for 40 said sub-piston, a main shaft provided with a crank, means for controlling said sub-piston positively throughout the entire cycle, said means comprising a link, a pivotal connection between said rod and one end of said 45 link, the other end of said link being movable with respect to the engine frame, means for guiding the movable end of said link, a member connecting said means directly to said crank, and means pivotally connecting 50 said power piston to said crank.

10. An internal combustion engine comprising a cylinder, a power piston and an imperforate sub-piston both arranged to reciprocate within said cylinder, said sub-piston being located between the combustion chamber and said power piston, a rod for 55 said sub-piston, a main shaft provided with a crank, means for controlling said sub-piston positively throughout the entire cycle, 60 said means comprising a link, a pivotal connection between said rod and one end of said link, the other end of said link being movable with respect to the engine frame, means for guiding the movable end of said link, 65 means for limiting the movement of said end of said link, a rocker arm, a rod pivotally connecting said link and said rocker arm, a member pivotally connecting said rocker arm directly to said crank, and means 70 pivotally connecting said power piston to said crank.

In testimony whereof, I have hereunto subscribed my name this 25th day of August 1922.

WILLIAM A. GILE.
